(57) **CLAIM**

The ornamental design for an elastic loop, as shown and described.

DESCRIPTION

FIG. 1 is a perspective view of a first embodiment thereof; FIG. 2 is a side view thereof (from the lower left side of FIG. 1);

FIG. 3 is a top view thereof;
FIG. 4 is an end view thereof (from the left end of FIG. 3);
FIG. 5 is an end view thereof (from the right end of FIG. 3);
FIG. 6 is a side view thereof (from the upper right side of FIG. 1);

FIG. 7 is a bottom view thereof;
FIG. 8 is a perspective view of a second embodiment thereof;

FIG. 9 is a side view thereof (from the lower left of FIG. 8);
FIG. 10 is a top view thereof;

FIG. 11 is an end view thereof (from the left end of FIG. 10);
FIG. 12 is an end view thereof (from the right end of FIG. 10);

FIG. 13 is a side view thereof (from the upper right side of FIG. 8); and,
FIG. 14 is a bottom thereof.

The evenly spaced broken lines are for the purpose of illustrating environment and form no part of the claimed design. The dot-dash-dot broken-away heavy weight lines in FIGS. 8, 10, and 14 themselves form no part of the claimed invention, and are provided to indicate that any portion of the article beyond what is shown forms no part of the claimed design. The short-long-short dash lines shown in the drawings are cut lines.
